Primary Examiner — Sandra Snapp*Assistant Examiner* — Leisha N Price(74) *Attorney, Agent, or Firm* — Terry M. Sanks, Esq.;
Beusse Sanks, PLLC(57) **CLAIM**

The ornamental design for a shackle, as shown and described.

DESCRIPTION

FIG. 1 is a front perspective view of the shackle;
FIG. 2 is a top view thereof;
FIG. 3 is a bottom view thereof;
FIG. 4 is a front view thereof, with the back view being a mirror image of; and,
FIG. 5 is a left side view thereof, with the right side view being a mirror image of.
The broken lines in the drawings illustrate portions of the shackle and form no part of the claimed design.
